UNITED STATES PATENT OFFICE.

OTTO F. PERSSON, OF ERIE, PENNSYLVANIA.

VARIABLE-PITCH PROPELLER.

1,316,862.

Specification of Letters Patent. Patented Sept. 23, 1919.

Application filed June 25, 1918. Serial No. 241,855.

To all whom it may concern:

Be it known that I, OTTO F. PERSSON, a citizen of the United States, residing at Erie, in the county of Erie, State of Pennsylvania, have invented certain new and useful Improvements in Variable-Pitch Propellers, of which the following is a specification.

The present invention relates to variable pitch propellers and especially to those intended for driving aeroplanes but is also applicable to the propulsion of vessels whose travel is wholly or partially in the water.

The object of my invention is to provide a propeller of improved construction in which the blades are so constructed and arranged that their angles can be changed for the purpose of varying the speed of the object propelled thereby; and in the case of a vessel so changed that the direction of its movement can be reversed. One of the important features of my improved construction is the arrangement of parts whereby the blades can be adjusted about their axes without the expenditure of much energy while on the other hand the stresses and shocks to which the blades are subjected are prevented from being freely transmitted to the operating handle or other device.

For a consideration of what I believe to be novel and my invention, attention is directed to the accompanying description and claims appended thereto.

In the drawings which are illustrative of my invention Figure 1 is a cross-section of a four-bladed propeller for an aeroplane; Fig. 2 is an axial section of the same; Fig. 3 is a view in elevation of the propeller; Fig. 4 is a view showing the propeller and its engine in side elevation; Fig. 5 is a modified form of the invention in axial section showing the adjusting mechanism of a two-bladed propeller; Fig. 6 is a cross-section of the same; Fig. 7 is a view in elevation of a propeller for a vessel, and Fig. 8 is an axial view of the same showing the blade adjusting means.

10 indicates the shaft of a prime mover such as an internal combustion engine or turbine. Secured to one end of it is a casing having as many radially extending tubular projections 11 as there are propeller blades. The casing is made in two principal parts 12 and 12^a, the former being keyed to the shaft and the latter secured to the first by a plurality of axially extending bolts 13, the whole forming a rigid structure.

Mounted on each tubular projection is a propeller blade 14 of suitable shape and size for the work to be performed. The blades may be of any suitable construction. In the present case each comprises a base which has a hollow spindle 15 formed integral therewith. On each spindle are two collars or shoulders 16 and 17, the former engaging an inner shoulder on the casing and the latter the finished outer face thereof. These collars prevent endwise movement of the blades and the collar 16 serves to resist centrifugal stresses.

The casing as before stated is in two parts and the plane of division coincides with the axes of the blades and hence by taking out the bolts 13, the parts can be separated and the blades easily removed. Formed integral with the spindle is a portion 18 which is made hollow to reduce its weight and mounted thereon is the blade proper. In this case the blade is made of relatively thin metal to reduce the weight and is secured to the part 18 by any appropriate means.

The inside of the spindle has a number of spirally arranged threads which mesh with corresponding threads on the blade actuator. In other words, each spindle in addition to acting as such forms a nut having screw threads of such character that when the co-operating screw is moved longitudinally thereof, the spindle and nut will be turned angularly about their axes. The blades are provided with actuators arranged in pairs. Each actuator comprises a portion 19 having spirally arranged screw threads adapted for engagement with those in the nut in the spindle. Moving the screw actuator toward

or away from the main shaft causes an angular movement of the spindle and blade in one direction or the other and in this manner changes the effective angle or pitch of the blade to cause a greater or lesser propulsive effect. Each screw 19 is formed integrally with or is rigidly attached to a sliding rack 20 which is located at one side of the main shaft and is held in position by a suitably arranged guide 21. The companion rack on the opposite side of the shaft is held in place by a similar guide 21. The second pair of racks are arranged at right angles to the first and have guides 26 of a construction similar to those described but extending at right angles thereto. All of

these guides are formed integral with the casing and being arranged in the form of a

hollow square render the casing very strong without being heavy.

Mounted on the main shaft and extending through the part 12^a of the casing is a sleeve 28 which is held from turning independently of the shaft by the spline 29. On the sleeve is mounted a grooved collar 30 which is retained in place between a shoulder and a clamping nut. On the inner end of the sleeve is formed the spiral gear 31, the angle of the teeth 32 being shown in dotted lines in Fig. 2. The angle of the gear teeth is such that axial movements of the gear causes lengthwise movements of the racks and is also such that the gear cannot be moved by reason of pressure exerted by the rack teeth. This gear is so positioned and of such length that it engages and actuates all four racks simultaneously. As will be seen the racks which actuate one pair of blades are located in the same plane and engage one end of the gear, while the racks which actuate the other pair of blades are located in a parallel plane and engage the other end of the gear.

In order to change the angular positions of the blades a forked lever 33, Fig. 4, is mounted on the engine 34 or other support and engages the grooved collar 30 on opposite sides. The lever is actuated by a rod 35, connected to a suitable handle, from a suitable place near the operator. Moving the sleeve and spiral gear endwise causes the teeth of the latter to move the racks in or out as the case may be. The racks in turn move the screws 19 longitudinally and in so doing cause the blades and their spindles to assume new angular positions. It will be seen that the reciprocating movements of the racks are at right angles to those of the sleeve, and that similar movements of the spirally threaded screws 19 result in angular movements of the blades. The angles of the teeth and threads are such that the sleeve and gear can adjust the angular positions of the blades but the blades themselves cannot move the gear and sleeve. In other words, an irreversible actuating mechanism is arranged between the sleeve and blades.

Referring to the arrangement shown in Figs. 5 and 6, the casing is made in two parts as before but the blades instead of being radial are slightly off-set from the axis of the main shaft 10. Splined on the main shaft is the sleeve 28 which carries the gear 31, the angular relation of the teeth being illustrated at 32, Fig. 5. 40 indicates a nut arranged to move longitudinally in guides 41. On one side of the nut are formed rack teeth 42 which mesh with the teeth on the gear 31. The spindle 43 of each blade is made solid in this case and formed thereon or rigidly secured thereto is a screw 44 having long spirally arranged

threads which co-operate with threads in the interior of the nut 40.

The action is as follows:—When the shaft 10 rotates it drives the blades in the usual manner. To change the angle of the blades the position of the gear 31 is adjusted longitudinally. This in turn moves the nuts 40 longitudinally but in a direction at right angles to the shaft axis and in so doing its threads acting on those of the screws 44 cause the latter to change the angular position or pitch of the blades to obtain the desired propulsive effect. It will be seen that the same irreversible arrangement of parts is provided in this construction as in the one previously described but that it is carried out in a slightly different manner.

In Figs. 7 and 8 my invention is shown applied to the propeller of a vessel, the construction of the propeller being essentially the same as described in connection with Figs. 1 and 2. 45 indicates the hull of the vessel through which the sleeve 46 of the propeller extends, suitable packing devices 47 and 48 being provided to keep out the water. It is to be noted that the sleeve 46 is integral with the part 12^a of the casing and extends into the ship, the purpose being to prevent water from having access to the blade operating mechanism. The gear 49 carrying sleeve 28 in this case is also made longer and where it terminates inside the vessel is provided with a circular rack 49. Meshing with the rack is gear 50 which is mounted on a cross-shaft 51. On the shaft 51 is also mounted a worm wheel 52 meshing with a worm driven by an electric or other motor 53. By adjusting the sleeve 28 the pitch of the blades can be changed as desired, the range of movement being sufficient to cause the blades to reverse the direction of movement of the vessel. For small boats the blades can be reversed by hand in the manner described in connection with Figs. 1 to 4; conversely power means can be employed for adjusting the angles of the blades for aeroplane propellers but ordinarily this is not necessary.

In accordance with the provisions of the patent statutes, I have described the principle of operation of my invention, together with the apparatus which I now consider to represent the best embodiment thereof, but I desire to have it understood that the apparatus shown is only illustrative, and that the invention can be carried out by other means.

What I claim as new and desire to secure by Letters Patent of the United States, is:—

1. In a device of the character described, the combination of a driving shaft, a casing rigidly attached to the shaft, propeller blades mounted on the casing which are capable of angular adjustment, a member splined on the shaft which is capable of

axial movement independent thereof, means located on the same side of the blades as the driving shaft for moving the member, toothed gear means for transforming axial movements of the member into reciprocating movements perpendicular to the shaft, and nut and screw means for transforming said reciprocating movements into angular movements of the blades.

2. In a device of the character described, the combination of a driving shaft, a casing rigidly attached to the shaft, propeller blades mounted on the casing which are capable of angular adjustment, a gear member splined on the shaft which is capable of axial movement independent of the shaft, racks located in the casing which are reciprocated in a direction perpendicular to the shaft by the gear member, and irreversible means which transform the reciprocating movements of the devices into angular motion and turn the blades on their axes without changing their diameter.

3. In a device of the character described, the combination of a driving shaft, a casing rigidly attached thereto, propeller blades carried by the casing, a sliding gear splined on the shaft and having spirally arranged teeth, racks meshing with and moved by the gear, and a nut and screw for each blade actuated by the racks for changing its angular position.

4. In a device of the character described, the combination of a driving shaft, a casing rigidly attached thereto, propeller blades carried by the casing, a gear splined on the shaft, means for moving the gear axially on the shaft, racks mounted in the casing for engagement with the gear and extending perpendicularly to the shaft, and nut and screw parts for changing the pitch of each blade, one of said parts being moved by the rack and the other being attached to the blade.

5. In a device of the character described, the combination of a driving shaft, a casing rigidly attached thereto, propeller blades pivotally mounted on the casing, a gear having spirally arranged teeth splined on the shaft, means for adjusting the gear, racks arranged on opposite sides of the gear and extending perpendicularly to its axis, and nut and screw parts for each blade located in the casing, certain of said parts being attached to the racks and the others to the blades.

6. In a device of the character described, the combination of a driving shaft, a casing which is composed of two principal parts, one of said parts being secured to the shaft, the other having an opening to receive the shaft, the plane of division being perpendicular to the shaft, means for uniting the parts of the casing, pivotally supported blades which are anchored against centrifugal forces in the casing, a gear having spirally arranged teeth, an actuating sleeve mounted in the casing, the sleeve extending through the shaft opening, racks on opposite sides of the gear which mesh therewith, and nut and screw means between the racks and blades for moving them angularly to change their pitch.

7. In a device of the character described, the combination of a driving shaft, a casing rigidly mounted thereon which is provided with blade supports, a spiral gear splined on the shaft, means for moving the gear axially, racks having teeth meshing with those on the gear, guides for the rack which also form a hollow square to brace the casing, spindles for the blades which also form nuts, and screws engaging the nuts which are moved by the racks to change the pitch of the blades.

8. In a device of the character described, the combination of a driving shaft, a divided casing rigidly mounted thereon which is provided with blade supports and also internal shoulders, blades mounted on the supports, spindles for the blades having collars which engage the shoulders, a sliding spiral gear mounted on the shaft, racks having teeth meshing with the gear, and nut and screw parts, certain of which are attached to the blade spindles and the others to the racks.

9. In a device of the character described, the combination of a driving shaft, a casing rigidly mounted thereon, a spiral gear which slides axially of the shaft within the casing, a sleeve which extends outside of the casing for moving the sleeve, actuating means for adjusting the sleeve, racks having teeth which mesh with those of the gear, angularly adjustable blades mounted on the casing, and nut and screw parts which are actuated by the racks for turning the blades on their axes.

In witness whereof, I have hereunto set my hand this 22 day of June, 1918.

OTTO F. PERSSON.
